DRYING APPARATUS

Wendell L. Martin, Cleveland, Ohio, assignor to
The Martin Brothers Electric Company, Cleve-
land, Ohio, a corporation of Ohio

Application July 1, 1932, Serial No. 620,353

13 Claims. (Cl. 34—26)

My invention relates to drying apparatus, and has particular reference to apparatus for use in drying hair or the hands, or the like, and a principal object of my invention is to provide a new 5 and improved apparatus of this type.

In the drawing accompanying this specification, and forming a part of this application, I have shown, for purposes of illustration, one form which my invention may assume, and in this 10 drawing:

Figure 1 is an enlarged horizontal sectional view of the embodiment herein illustrated taken on the line 1—1 of Figure 3, and showing one 15 characteristic operation of the apparatus,

Figure 2 is a similar horizontal sectional view of said embodiment showing another characteristic operation of said apparatus,

Figure 3 is a side elevational view of said 20 embodiment, portions of the pedestal being broken away, while

Figure 4 is a transverse vertical sectional view, taken on the line 4—4 of Figure 2.

The embodiment of my invention herein shown 25 comprises a dome-shaped housing, or casing 5, having a beaded front edge 6, tapering toward the rear, and terminating in a rear wall 7 having an opening 8 surrounded by a flange 9, and also having an opening 10 surrounded by a flange 11.

Disposed within the housing, or casing 5 is an 30 insert comprising a dome-shaped shell 12, at its rear end provided with a tubular extension 13 extending through the flanged opening 10, extending in substantially parallel spaced relation with respect to the housing 5 and terminating short 35 of the forward extremity of said housing, defining a passage 14, and at its forward end supports the forward portion, as by an integral connection, of a dome-shaped hood member 15, forming a

chamber 16, extending in spaced relation with respect to the shell 12 and defining therewith a 40 passage 17, communication being afforded between the chamber 16 and passage 17 by a plurality of annularly arranged apertures 18 covered by a strip of screen 19 secured by rivets 20 to the hood member 15. A web 20 of screen is disposed to span the space between the forward portions of the shell 12 and housing 5, being secured in position by screws 21.

Disposed at the rear of the housing 5 is a 45 circular block 22 of material, provided with an opening 23 surrounded by a boss 24, and with an opening 25 surrounded by a boss 26, the boss 24 extending into the flange 9 surrounding the opening 8, and the boss 26 extending into the tubular

extension 13, the block being secured in position by a plurality of pins, only one of which is shown, as at 27. Cooperating with the block 22 is a cup-shaped supporting member 28 into which the block 22 is rotatably seated, and rotatably secured by a rivet 29, limited in rotation by a pin and slot arrangement 30, the supporting member 28 having an opening 31 surrounded by a boss 32 and an opening 33 surrounded by a boss 34, the openings 31 and 33 being so located as to come 5 into registry with the openings 23 and 25 of the block 22, a washer 35 being interposed between the block 22 and supporting member 28 and secured to the latter by any suitable means, and provided with openings registering with the openings 31 and 33. The supporting member 28 is also provided with oppositely disposed radially extending studs 36 accommodated in the end portions of furcations forming part of a supporting pedestal 37.

Secured to the rear of the supporting member 28 is a circulating unit comprising a fan casing 38 enclosing a centrifugal fan 39 of the turbine type mounted upon the armature shaft 40 of a motor 41 secured to the casing 38 by bolts 42, the axis 25 of rotation of the fan 39 being arranged substantially at right angles to the axis of the housing 5, and communicating with the eye of the fan 39 and forming part of the fan casing 38 is a curved conduit pipe 43 the open end of which 30 seats about and is secured to the boss 32 surrounding the opening 31 in the supporting member 28, and also formed as a part of the fan casing 38 is a conduit 44 arranged in line with the circumferential periphery of the fan 39, and having its outer end fitted over and secured to the boss 34 and communicating with the opening 33 in the supporting member 28. Disposed within the conduit 44 is a heating coil 45 insulated therefrom, and secured in position by suitable securing means as indicated at 46.

When the motor 41 and fan 39 are energized and assuming the apparatus to be in the position shown in Figure 1, pressure is reduced in the passage 14 causing movement of air through the opening 8 into the conduit 43 and thence to the fan 39 which discharges such air outwardly through the conduit 44 and into the passage 17, passing thence into the chamber 16 through the openings 18, over the head of the subject treated, and coming into the zone of low pressure at the open end of the passage 14 a material part of such air is entrained, enters such passage and is recirculated, as clearly shown by the arrows 45 in Figure 1.

To reverse circulation of air through the apparatus the casing may be grasped by the operator and rotated as permitted by the rotatable connection of the block 22 with the supporting member 28, to bring the openings 8 and 23 into alignment with the conduit 44, and to bring the openings 13 and 25 into alignment with the conduit 43, wherefore air will be circulated as indicated by the arrows in Figure 2, air entering the chamber 16, passing through the apertures 18 into the passage 17 thence through the tubular extension 13 and conduit 43 to the fan 39 being then discharged into the extension 44, heated, thence discharged into the passage 14 and outwardly, and by reason of the air of low pressure in the chamber 16 a material portion of this same air again enters the chamber 16 and is recirculated.

Thus it is apparent that the direction of recirculation of the air passing through the apparatus may be reversed at will by a simple operation, and more rapid and efficient operation effected, with a material gain in heat energy conservation.

It will be apparent that the embodiment herein described accomplishes the principal object of the invention, and is adapted for uses and purposes not herein particularly referred to, and may be variously changed and modified without departing from the spirit of my invention, and accordingly it will be understood that such embodiment is illustrative only and my invention is not limited thereto.

I claim:

1. Apparatus, as of the type described, for subjecting a person to the action of a stream of gaseous-like fluid, comprising: an open-front housing having a plurality of orifice areas, and means within said housing defining a plurality of cooperating passages communicating with said orifice areas; a circulating unit cooperating with said housing, and having a suction inlet and a discharge outlet; means for supporting said circulating unit; said housing being shiftable with respect to said circulating unit to effect selective communication of said suction inlet and said discharge outlet of said circulating unit with the cooperating passages of said housing; said housing also comprising means whereby gaseous fluid discharged from one passage is entrained in the stream of gaseous fluid entering the other passage and thus recirculated.

2. Apparatus, as of the type described, for subjecting a person to the action of a stream of gaseous-like fluid, comprising: an open-front housing having a plurality of orifice areas, one embracing another, and means within said housing defining a plurality of cooperating passages communicating with said orifice areas; a circulating unit cooperating with said housing, and having a suction inlet and a discharge outlet; said housing being swiveled with respect to said circulating unit to effect selective communication of said suction inlet and said discharge outlet of said circulating unit with the cooperating passages of said housing, whereby the plurality of orifice areas alternately may serve for inlet and discharge of the gaseous fluid circulated; said housing also comprising means whereby gaseous fluid discharged from one passage is entrained in the stream of gaseous fluid entering the other passage and thus recirculated.

3. Apparatus, as of the type described, for subjecting a person to the action of a stream of gaseous-like fluid, comprising: an open-front

housing having a plurality of orifice areas, and means within said housing defining a plurality of cooperating passages communicating with said orifice areas; a circulating unit cooperating with said housing, and having a suction inlet and a discharge outlet; means for supporting said circulating unit; said housing being swiveled with respect to said circulating unit to effect selective communication of said suction inlet and said discharge outlet of said circulating unit with the 10 cooperating passages of said housing.

4. Apparatus, as of the type described, for subjecting a person to the action of a stream of gaseous-like fluid, comprising: an open-front housing having a double-walled concave member 15 for the reception of a part of a subject to be treated, and cooperating with said housing to provide a plurality of orifice areas and a plurality of cooperating passages communicating with said orifice areas; a circulating unit cooperating with said housing, and having a suction inlet and a discharge outlet; said housing and said circulating unit being rotatably arranged with respect to each other to effect selective communication of said suction inlet and said discharge outlet of said circulating unit with the 20 cooperating passages of said housing; said housing also comprising means whereby gaseous fluid discharged from one passage is entrained in the stream of gaseous fluid entering the other passage and thus recirculated.

5. Apparatus, as of the type described, for subjecting a person to the action of a stream of gaseous-like fluid, comprising: an open-front housing having a double-walled concave member 35 for the reception of a part of a subject to be treated, and cooperating with said housing to provide a plurality of orifice areas and a plurality of cooperating passages communicating with said orifice areas; a circulating unit cooperating with said housing, and having a suction inlet and a discharge outlet; said housing and said circulating unit being shiftable relatively to each other to effect selective communication of 40 said suction inlet and said discharge outlet of said circulating unit with the cooperating passages of 45 said housing.

6. Apparatus, as of the type described, for subjecting a person to the action of a stream of gaseous-like fluid, comprising: an open-front 50 housing having a plurality of orifice areas, and means within said housing defining a plurality of cooperating passages communicating with said orifice areas; a circulating unit cooperating with said housing, and having a suction inlet and a discharge outlet, said housing and said circulating unit being shiftable relatively to each other to effect selective communication of said suction inlet and said discharge outlet of said circulating unit with the cooperating passages of said housing.

7. A drier comprising: a dome-shaped housing having an open front end and a closed rear end, the latter being provided with a pair of openings; a shell secured within said housing and therewith defining a passage open at the front of the housing and communicating with one of the openings in the rear of said housing; a hood member carried by said housing and with the shell defining a second passage opening into said hood member 70 and communicating with the other opening in the rear of said housing; and a circulating unit comprising a motor and fan and enclosing casing, the latter having a suction inlet and a discharge outlet; and means movably connecting said circulat- 75

- ing unit and said housing to permit relative shifting therebetween to effect selective registry of the suction inlet and discharge outlet with the openings in the rear of said housing.
5. 8. Apparatus, as of the type described, for subjecting a person to the action of a stream of gaseous-like fluid, comprising: an open-front housing having a plurality of orifice areas, and means within said housing and supported thereby defining a plurality of cooperating passages communicating with said orifice areas, one of said passages intersecting the other passage; a circulating unit cooperating with said housing, and having a suction inlet and a discharge outlet; 10 means for supporting said circulating unit; said housing and the means therein being rotatable with respect to said circulating unit to effect selective communication of said suction inlet and said discharge outlet of said circulating unit with the cooperating passages of said housing; said housing also comprising means whereby gaseous fluid discharged from one passage is entrained in the stream of gaseous fluid entering the other passage and thus recirculated.
15. 9. Apparatus, as of the type described, for subjecting a person to the action of a stream of gaseous-like fluid, comprising: a casing construction having orifice areas, and including a plurality of nested elements including an outer casing, a hood member defining a cavity for the reception of the object to be treated, and an intermediate shell member, together defining a triple-walled construction, said casing having a portion spaced from said shell to define an air passage, communicating with one of said orifice areas, and said shell being spaced from said hood member to define another air passage, communicating with another of said orifice areas; a circulating unit having a suction inlet and a discharge outlet; 20 means for supporting said circulating unit; said triple-walled construction being relatively shiftable with respect to said circulating unit to effect selective communication of said suction inlet and said discharge outlet of said circulating unit with said air passages; and said apparatus comprising means whereby gaseous fluid discharged from one passage is entrained in the stream of gaseous fluid entering the other passage and thus recirculated.
25. 10. Apparatus, as of the type described, for subjecting a person to the action of a stream of gaseous-like fluid, comprising: a casing construction having orifice areas, and including a plurality of nested elements including an outer casing, a hood member defining a cavity for the reception of the object to be treated, and an intermediate shell member, together defining a triple-walled construction, the walls thereof being substantially parallel throughout their coinciding lengths, said casing having a portion spaced from said shell to define an air passage, communicating with one of said orifice areas, and said shell being spaced from said hood member to define another air passage, communicating with another of said orifice areas; and fluid-circulating means communicating with both of said passages, operating to indraw through one of said orifice areas, an inflowing stream of fluid into one of said passages, and to expel said fluid from said other passage in an outflowing stream, through said other orifice area; said passages and fluid-circulating means being constructed for reversible operation, whereby the direction of flow of fluid therethrough is reversed.
30. 11. Apparatus, as of the type described, for sub-
- jecting a person to the action of a stream of gaseous-like fluid, comprising: a casing construction having orifice areas, and including a plurality of nested elements including an outer casing, a hood member defining a cavity for the reception of the object to be treated, and an intermediate shell member, together defining a triple-walled construction, said casing extending substantially beyond the front ends of said hood member and shell and having a portion spaced from said shell to define an air passage, communicating with one of said orifice areas, and said shell being spaced from said hood member to define another air passage, communicating with another of said orifice areas, one of said passages intersecting the other passage; and fluid-circulating means communicating with both of said passages, operating to indraw through one of said orifice areas, an inflowing stream of fluid into one of said passages, and to expel said fluid from said other passage in an outflowing stream through said other orifice area; and said apparatus comprising means whereby gaseous fluid discharged from one passage is entrained in the stream of gaseous fluid entering the other passage and thus recirculated.
35. 12. Apparatus, as of the type described, for subjecting a person to the action of a stream of gaseous-like fluid, comprising: a casing construction having orifice areas, and including a plurality of nested elements including an outer casing, a hood member defining a cavity for the reception of the object to be treated, and an intermediate shell member, together defining a triple-walled construction, said casing having a portion spaced from said shell to define an air passage, communicating with one of said orifice areas, and said shell being spaced from said hood member to define another air passage, communicating with another of said orifice areas, and one of said passages intersecting the other passage; a circulating unit having a suction inlet and a discharge outlet; means for supporting said circulating unit; said triple-walled construction and said circulating unit being swiveled with respect to each other to effect selective communication of said suction inlet and said discharge outlet of said circulating unit with said air passages; and said apparatus comprising means whereby gaseous fluid discharged from one passage is entrained in the stream of gaseous fluid entering the other passage and thus recirculated.
40. 13. Apparatus, as of the type described, for subjecting a person to the action of a stream of gaseous-like fluid, comprising: a casing construction having orifice areas, and including a plurality of nested elements including an outer casing, a hood member defining a cavity for the reception of the object to be treated, and an intermediate shell member, together defining a triple-walled construction, the walls thereof being substantially parallel throughout their coinciding lengths, said casing having a portion spaced from said shell to define an air passage, communicating with one of said orifice areas, and said shell being spaced from said hood member to define another air passage, communicating with another of said orifice areas; and fluid-circulating means communicating with both of said passages, operating to indraw through one of said orifice areas, an inflowing stream of fluid into one of said passages, and to expel said fluid from said other passage in an outflowing stream, through said other orifice area.
